UNITED STATES PATENT OFFICE.

EPHRIAM A. FOSTER, OF MASSILLON, OHIO.

TEETER CAR.

Application filed October 21, 1925. Serial No. 63,870.

This invention relates to an improvement in teeter-cars.

The object of my invention is to provide a teeter-car or small wagon to be used for the enjoyment of children.

A still further object of this invention is to provide such a vehicle with a spring-board seat which is moved vertically in a swinging motion during the longitudinal movement 10 of the car or wagon, so as to give a seesaw action to the seat, and to move the child up and down with such seesaw action.

My invention comprises a small wagon made very similar to the ordinary child's 15 wagon, but it may be from six to twelve feet long; and such a wagon is provided with a pivoted or swinging seat-board which is connected by means of a link with a crank which is formed in the axle or axles 20 of the car in order to move one or both ends of the board in a swinging upward movement. Suitable means may also be provided for guiding the car, if desired. Thus when the children are seated on the swinging 25 board or seat, they are moved up and down in a seesaw action by and during the movement of the car over the ground or floor.

In the accompanying drawings:

Fig. 1 is a side elevation, partly in section of one form of my invention;

Fig. 2 is a top plan view of the same;

Fig. 3 is a bottom plan view thereof;

Fig. 4 is a side elevation, partly in section of a modified form of my invention;

Fig. 5 is a bottom plan view of the same; and

Fig. 6 is a bottom plan view of still another form of my invention.

In the form of the invention shown in Figs. 1, 2, and 3, the wheels 1 are affixed to the axles 2 of the car, which axles are mounted in bearings in the braces 3 which support the body 4 of the car. This body may or may not be provided with side-boards 45 as desired, but the bottom 5 thereof has provided thereon (substantially equidistant from its ends) the supports 6 for the swinging board 7, the latter being pivoted to the supports as at 8. Links 9 are pivoted to the outer ends of the swinging-board 7, as at 10, and the lower ends of these links are pivoted on the cranks 11 formed in the axles 2. The links 9 extend through the elongated slots 12 in the bottom of the body 55 4, as shown in Figs. 1 and 3.

A suitable steering-rod or loop 13 is con-

nected with the front axle 2, and extends around the front of the body 4, and over the front end of the swinging-board 7, so that the car may be guided by a child riding 60 on the front end of this board.

Railings 14 are provided on each side of the swinging plank 7, as shown in Fig. 2, for preventing a very small child from falling off; and suitable handles 15 may also 65 be provided adjacent the ends of the board for the same purpose.

The form shown in Figs. 4 and 5 is in the nature of a spring-board, in which only one end of the spring-board 16 is allowed to 70 swing, the opposite end thereof being secured in a fixed position at 17 to the bottom plate 18 of the body. The swinging end of this spring-board 16 is provided with the usual link 9, which is connected with the 75 crank 11 on the axle 2 similar to the form shown in Figs. 1, 2 and 3. As clearly shown in Fig. 5, the front axle 2 of this form is pivoted as at 19 to the bottom plate 18 of the body, and this front axle is provided 80 with a substantially V-shaped swinging brace 20, which extends above the transverse brace 21 forming a fifth wheel for allowing the front wheels 1 to be turned 85 for guiding the car. A suitable steering-yoke 22 is connected with the front axle for turning and steering the same.

The form of car shown in Fig. 6 differs from that shown in Figs. 1, 2 and 3, merely in the provision of two swinging-boards 23 90 instead of one, as shown in said figures; and these swinging boards 23 shown in Fig. 6 move in opposite directions, so that the end of one will be up while the corresponding end of the other will be down. To accomplish this, it will be noted that the cranks 24 formed on the axles 2 are bent in opposite directions from each other in order to guide the links 9 in their proper relation.

As the car is pushed over the ground or 100 floor upon which it is operated, it will be noted that motion is applied to the axles 2 and the crank-arms 11 formed thereon from the wheels 1, which crank-arms move the links 9 upward and downward in a reciprocating movement which gives a rocking movement to the ends of the swinging-boards upon which the children are riding. Thus as the car is moved over the surface, the children riding thereon are given a seesaw or spring-board motion, much to their 110 delight. Any suitable steering-gear may be

provided for guiding the car, if it is desired.

I claim:

- 5 1. A vehicle of the character described including a supporting frame, a swinging board pivotally mounted thereon, axles for supporting the front and rear of said frame, wheels mounted on the axles, the opposite ends of the swinging board being freely swinging and entirely disconnected from the frame, and means connecting both of the opposite ends of the swinging board with the axles, each thereof with a corresponding axle, for imparting an up and down movement thereto by the propelling of the vehicle.
- 10 2. A vehicle of the character described including a supporting frame, a swinging board having one end thereof fixed to said frame and having the opposite end thereof entirely disconnected therefrom, and means connected with said last-mentioned end for imparting an up and down movement thereto by the propelling of the vehicle.
- 15 3. A vehicle of the character described including a supporting frame, axles for supporting the front and rear of said frame, wheels mounted on the opposite ends of said axles, a swinging board having one end thereof fixed to the front end of said frame and having the opposite end thereof entirely disconnected therefrom, and means connect-

ing the rear axles with said last-mentioned end for imparting an up and down movement thereto by the propelling of the vehicle.

35 4. A vehicle of the character described including a supporting frame, supporting wheels and axles for the frame, a swinging board mounted on the frame, and a guiding loop connected with at least one of the axles 40 and extending into close proximity with the swinging board for turning said axle to guide the vehicle.

45 5. A vehicle of the character described including a supporting frame, a swinging board mounted on the frame, front and rear axles and wheels for supporting said frame, and a loop pivotally connected with at least one of the axles and extending into close proximity with the swinging board for turning 50 said axle to guide the vehicle.

55 6. A vehicle of the character described including a supporting frame, front and rear axles and wheels for supporting said frame, a swinging board mounted on said frame, and a loop pivotally connected with the front axle and extending over and in close proximity to the swinging board for turning said front axle to guide the vehicle.

60 In testimony whereof I affix my signature.

EPHRIAM A. FOSTER.
